UNITED STATES PATENT OFFICE.

ALFRED GRIEB, OF ELIZABETH, NEW JERSEY, ASSIGNOR TO THE SINGER MANUFACTURING COMPANY, A CORPORATION OF NEW JERSEY.

OVERSEAMING SEWING-MACHINE.

1,243,159.

Specification of Letters Patent. Patented Oct. 16, 1917.

Application filed July 21, 1913. Serial No. 780,126.

To all whom it may concern:

Be it known that I, ALFRED GRIEB, a citizen of the United States, residing at Elizabeth, in the county of Union and State of 5 New Jersey, have invented certain new and useful Improvements in Overseaming Sewing-Machines, of which the following is a specification, reference being had therein to the accompanying drawings.

10 This invention relates to an improvement in overseaming sewing machines, and more particularly to that class of mechanism comprising a reciprocating needle and two loop-carrying implements coöperating there- 15 with, one of which implements, a threaded looper, passes its thread through the needle-loop below the work and serves to hold said loop while its own loop is seized by the second loop-carrying implement and drawn 20 over the edge of the work into the path of the needle. The invention provides compact and efficient mechanism of this type, especially adapted to act upon heavy fabrics; said mechanism including means for 25 perfectly controlling the two threads during every stage of the overseaming operation.

In the present embodiment of the invention the needle-bar, carrying the usual eye- 30 pointed needle, is reciprocated by a link connection between the same and the outer end of the rock-shaft mounted within the overhanging arm of the frame, an oscillating movement being imparted to said rock- 35 shaft from a crank upon the driving shaft by an intermediate pitman. The driving shaft is provided with a series of eccentrics one of which actuates a rock-lever which in turn imparts operative movements to an 40 open-jawed loop-spreading hook and to thread-controlling members for the two threads; a second eccentric actuates a rock-arm which serves as a carrier for the threaded looper and for a needle-guard; and a 45 third eccentric actuates a rock-lever which imparts reciprocating movements to the feed-dog, said feed-dog being mounted upon a sleeve carried by a fourth driving shaft eccentric which causes said feed-dog to rise 50 and fall and thus complete the four-motion feed.

The construction is such that the threaded looper operates below the work in a path inclined to, and crossing, the path of the 55 loop-spreading hook. The blade of the

threaded looper moves in an arc from a point below the needle-eye in its extreme lower position to a point immediately below the work and slightly beyond its edge; said arc extending diagonally of the work- 60 plate so that the looper-blade passes through the needle-loop below the work at the rear of the needle and presents its own loop to the hook at a point slightly beyond the edge of the work and opposite the side 65 of the needle. The advancing threaded looper crosses the path of the hook at such point, the hook in its movement seizing the looper-loop and drawing one limb thereof in front of the needle, so that the latter in 70 its descent may pass between the two limbs of said loop. To accomplish this result the loop-spreading hook is sustained from inclined bearing members, so that as the hook moves upwardly and outwardly to spread 75 the looper-loop over the work, it also moves forwardly of the needle, the entire movement being in an inclined path relative to the line of feed. During the aforesaid operations thread-controlling arms carried by 80 the hook-operating rock-lever, in coöperation with a thread-drawing member carried by the needle-bar, perform the necessary slack-forming and take-up operations and 85 completely control the two threads.

The loop-spreading hook may be replaced with a second eyed looper carrying a thread whose loop is passed through that of the primary looper and presented for 90 passage of the needle to form a three-thread overseam, such overseam having been heretofore effected by similar mechanism in a manner well understood in the art.

Referring to the drawings, Figure 1 is a 95 front side elevation, partly in section, of a sewing machine embodying my improvements. Fig. 2 is a front end elevation of the same. Figs. 3, 4 and 5 are detail perspective views of the threaded looper, 100 needle, and loop-spreading hook, and their connections, showing the relative positions of such members in different stages of their operation. Fig. 6 is a top plan view of the 105 loop-spreading hook, the threaded looper, and their connections. Fig. 7 is a view of two pieces of material united and overseamed by the present construction.

Referring to the drawings, 1 represents the bed-plate of a frame having the usual 110

overhanging arm 2 with head 3, the latter being provided with bearings for the needle-bar 4 carrying the eye-pointed needle 5. The needle-bar is provided with the usual 5 fixed collar 6 connected by means of link 7 to crank-arm 8 mounted upon the rock-shaft 9 journaled in the overhanging arm of the frame and deriving operative movements from driving shaft 10 by means of 10 pitman 11 and crank 12. In the head of the frame is journaled the usual presser-bar 13 carrying presser-foot 14.

In the present instance the needle-bar carries a thread-drawing member 15, the 15 two thread-engaging arms of which extend outwardly beyond the head 3 through suitable slots formed in said head. Said arms are adapted to draw the needle thread at proper intervals and to coöperate with 20 the forked thread-guides 15^x embracing its path of movement and with the thread-releasing arm 16, as hereinafter more fully described.

The top of the bed-plate is provided with 25 two upwardly extending lugs 17 inclined with respect to the line of feed and serving to support shaft 18 which affords a bearing for rock-arm 19. Rock-arm 19 serves as a carrier for the threaded looper 20 and 30 needle-guard 21, the shank of the looper entering an opening formed in the outer end of said arm and being fixed therein by set-screw 19^x. The needle-guard, which may be of any suitable form, is provided with a 35 foot which is fastened to the face of said arm by screws, as shown in Fig. 1. Threaded looper 20 is given its operative movements by driving shaft eccentric B embraced by the strap 22' 22'' of a short pitman 22, connected to crank-arm 23 upon the rock-arm hub by ball-stud 24, the ball of the latter fitting a socket formed in pitman 22, undue vibration of the two members thus connected being prevented by in- 40 45 intermediate slotted spring-plate 25. Rock-arm 19 also carries a thread-guide 26 of suitable form, as shown in Fig. 1.

Threaded looper 20 has its operative movements confined to a path below the 50 work, its function being to pass its thread through the needle-loop and to hold the latter until its own loop is seized by the spreading hook and is carried by it over the edge of the work and into the path of the 55 needle, as hereinafter more fully described.

Extending from the overhanging arm 2 are lugs 27, one lug being disposed below the other, said lugs affording bearings for the inclined shaft 28 to which rock-lever 29 60 is rigidly connected, the shaft being arranged diagonally of the work-plate. The front end of rock-lever 29 is connected by a stud-screw 30 with the apertured upper arm of the elbow-lever 31. The lateral arm 65 of elbow-lever 31 is provided with a boss

31^a adapted to receive the shank of loop-spreading hook 32 which is secured in said collar by a set-screw. The intermediate or elbow portion of lever 31 is apertured to receive stud-screw 30^x carried by the rock-arm 33, having its hub 33^x journaled upon a stud inclined and arranged with respect to the work-plate similarly to shaft 28, and sustained by the depending boss 3^x of the head 3. The rear end of rock-lever 29 passes 70 through an opening formed in the upwardly extending portion of the frame and carries the ball-stud 34 which is embraced by the strap 35^x of the actuating pitman 35 provided at its lower end with the strap 36^x embracing the driving shaft eccentric A. It will be seen that the arrangement of rock-lever 29 and rock-arm 33 permits said members to move the loop spreading hook in a 75 plane inclined relatively to a vertical plane 80 through the line of feed, as will be apparent from an inspection of Figs. 2 and 6.

Fixed upon the rear arm of rock-lever 29 and adjacent stud 34 by means of screw 38 is the upwardly extending thread-controlling arm 37. Shaft 28 has fixed thereon beyond lower lug 27 by means of the set-screw 40 the downwardly extending thread-controlling arm 39. The outer ends of controller members 37 and 39 are apertured to receive respectively the needle-thread and the looper-thread.

The feed-dog 41 is mounted upon a strap which embraces driving shaft feed-lift eccentric C, shown in dotted lines Fig. 1, 100 from which it derives its rising and falling movements. The work-advancing or feeding movements of the feed-dog are derived from the driving shaft eccentric D, pitman 42, segmental arm 43 and link 44, the latter 105 being pivotally connected with the feed-dog. The length of feeding movement may be varied by shifting the stud-bolt 42^x upon the segmental arm 43.

In threading the machine, the needle 110 thread is passed through tension device 45, and the eye of thread-controller member 37 and thence through the thread-guide 15^x and over thread-releasing arm 16 to the needle 5. The lower or looper thread is 115 passed through tension device 46, thread-controller arm 39 and thread-guide 26, and thence through the thread-eyes of looper 20, as shown in Fig. 1.

In the operation of the machine, rotation 120 of the driving shaft will impart through rock-shaft 9, reciprocatory motion to the needle-bar. A little after the needle penetrates the work, the parts assume the positions shown in Fig. 3. As the needle continues its descent, eccentric B moves pitman 22 upward and threaded looper 20 advances to seize the needle-loop. In the meantime the loop-spreading hook moves in an arc 125 from a position above the work to below 130

the upper end of the threaded looper-path and slightly beyond the edge of the work; and the thread-controller arm 37 is carried to the left, thereby giving up just enough 5 thread to the needle, so that in its descent to extreme lower position it will also draw up the slack in the previously formed needle-loop and set the stitch against the tension of the device 45, without pulling thread from the supply. Therefore when the needle reaches its lowest position, the needle-thread is taut. To prevent the contracting tendency of the thread from stealing a portion 10 of the needle-loop as the needle starts to rise, the thread-giving movement of the thread controller arm 37 is caused to continue during the pause of the needle in its lowest position, thus relieving the strain on the thread before the loop presenting operation. At the same time the thread-controller arm 39 is carried upwardly to draw up the slack not required by the threaded 15 looper during its advance.

In Fig. 4 the parts are shown in the positions they assume immediately prior to the needle-loop seizing operation, the work-plate being indicated by dotted lines. As the threaded looper continues its advancing movement from the position shown in Fig. 25 4, and as the looper seizes the needle-loop, hook 32 remains motionless for a brief period, in the dead-center position of eccentric A with respect to pitman 35, controller-arm 37 likewise remaining motionless, and 30 the rising of the needle increasing the slack for the loop-seizing operation. The continued rotation of eccentric A moves pitman 35 downwardly thus rocking lever 29 upwardly and moving hook 32 upwardly and 35 forwardly until the latter, crossing the path of the advancing threaded looper, seizes the looper-loop at a point beyond the edge of the work and slightly below the same, the needle meanwhile rising above the throat-plate and thread-controller 37 moving to 40 the right.

As the needle rises from its position immediately above the throat-plate, the outer end of rock-arm 29 continues its upward movement and carries arm 33 upwardly and rocks elbow-lever 31 upon its fulcrum 30^x, thereby carrying hook 32 to the position shown in Fig. 5, the looper meanwhile having advanced to its extreme upper position. 45 As the hook continues its movement, leaving the position shown in Fig. 5, the looper recedes, and the hook in its movement carries one limb of the looper-loop directly in front of the needle (Fig. 1), the other limb 50 of said loop being carried to the rear of the needle by the feed, and the needle-loop being drawn forwardly on the looper-blade.

The needle during its rise as aforesaid slides upon the needle-thread held taut below the work by the looper-blade, while con-

troller-arm 37 moves to the right, thereby drawing thread from the source of supply for the succeeding descent of the needle, and controller-arm 39 moves to the left to form sufficient slack in the looper thread 70 to permit the hook to spread the looper-loop over the work.

During the pause of the hook in the dead-center position of eccentric A, the needle point passes between the two limbs of the 75 looper-loop, while the threaded looper recedes sufficiently to release the needle-loop.

To draw up and partially set the released needle-loop locked below the work by the looper-loop, as the needle descends the two 80 arms of thread-drawing member 15 engage the needle thread and draw the needle-loop toward the work, the needle sliding down the thread until it enters the work. At this point the inclined face of thread releasing 85 member 16 carries the needle thread out of engagement with the arms of the thread drawing member, thus leaving slack below the thread-eyes of guide 15^x for the work-penetrating movement of the needle. 90

As the needle-point approaches the work, the hook recedes, while thread-controller arm 37 advances to furnish slack thread, and thread-controller arm 39 moves upwardly. The hook releases the looper-loop 95 as the needle-point enters the work while the upwardly moving controller arm 39 serves to draw said loop taut around the needle; and the needle, in its continued descent below the work, completely sets the released 100 needle-loop upon the looper-thread loop on the under face of the work. The hook continues its movement to a point beyond the edge of the work and above the work-plate, from which point it moves downwardly in 105 an arc extending below the work-plate the parts assuming the initial position shown in Fig. 3 for the succeeding stitch-forming cycle. It will be noted that the looper-blade moves forwardly, *i. e.*, toward the operator, 110 and upwardly as it projects its loop through the needle-loop. It is therefore necessary to cause the loop-spreading hook 32 to move forwardly and upwardly close by the side of the looper-blade in order that the hook 115 may, with certainty, seize the looper-loop. It has been found by experiment that, by inclining the axes of the parts 28, 30, 30^x and 33^x slightly to the vertical plane through the line of feed, the hook 32 is caused, not 120 only to seize the looper-loop as above described, but also to thereafter move above and across the line of feed more nearly at a right angle thereto than it otherwise would. The hook 32 is thus caused to move 125 to a position closely in front of the needle, as shown in Figs. 1 and 2, to bring the looper-loop directly under the needle, the feed having in the meantime moved the work a stitch-length. After the descending 130

needle has entered the looper-loop the hook 32 retracts, and by virtue of the above described positioning of the parts 28, 30, 30^x and 33^x, it is enabled to retract from its 5 position closely in front of the needle without striking the same.

Having thus set forth the nature of the invention, what I claim herein is:—

1. In an overseaming sewing machine, the 10 combination with a needle, a work-support, and means for reciprocating the needle, of a threaded looper mounted to operate below said work-support, a coöperating loop engaging member and a movable fulcrum 15 therefor, a rock arm and a fixed fulcrum therefor above the work-support, a connection between said rock arm and the said loop engaging member, and means whereby actuation of said rock arm will operate said 20 loop engaging member toward and from the work-support and in a path inclined to the line of feed.

2. In an overseaming sewing machine, the combination with a needle, a work-support, 25 and means for reciprocating the needle, of a threaded looper mounted to operate below said work-support, a coöperating loop-engaging member mounted above the work-support, a movable fulcrum therefor, a rock- 30 arm actuated upon a fixed fulcrum, a connection between said rock-arm and the said loop-engaging member, actuating means for said rock-arm adapted to cause said loop-engaging member to dwell while the needle 35 enters well into the loop presented thereby, and means whereby actuation of said rock-arm will operate said loop-engaging member toward and from the work-support in a forwardly inclined plane.

40 3. In an overseaming sewing machine, the combination with a horizontal work-support, a needle and means for reciprocating the same, of two coöperating loop-engaging members moving in intersecting paths and 45 supported respectively upon opposite sides of said work-support, and means adapted to operate the upper of said loop-engaging members in a plane inclined relatively to the vertical plane through the line of feed, said 50 means including a rock-arm operating above the work-support and having an interval of rest during the descent of the needle.

4. In an overseaming sewing machine, the combination with a frame comprising a 55 work-support, a standard, and an overhanging arm supported by said standard, of a needle, and an actuating shaft therefor within said overhanging arm, a threaded looper mounted to operate below said work- 60 support, a coöperating loop-engaging member supported above the work-support, a rock-arm adapted to transmit movement to said loop-engaging member in a plane inclined forwardly of the needle, an eccentric 65 upon the driving-shaft, and an eccentric rod

within the standard and operatively connected to said rock-arm.

5. An overseaming sewing machine, having in combination, a needle, a work-support, a threaded looper mounted to operate 70 below said work-support, a rock-arm mounted in a bearing disposed above said work-support and inclined relatively to the line of feed, actuating means therefor, a second rock-arm mounted in similarly inclined bearings above said work-support, a loop engaging member, and an elbow-lever connecting said rock-arms and serving as a carrier 75 for said loop-engaging member.

6. In an overseaming sewing machine, the 80 combination with a work-support, a needle and means for reciprocating the same, of a loop-engaging member mounted to operate both below and above said work-support, a rock-arm mounted above said work-support 85 and connected to said loop-engaging member, thread-controlling arms carried by said rock-arm, and operating mechanism for the rock-arm adapted to hold the same motionless during periods of the needle reciproca- 90 tion.

7. In an overseaming sewing machine, the combination with a reciprocating needle, and actuating means therefor, of two loop-engaging members movable in intersecting 95 paths, means including a rock-arm for operating one of said loop-engaging members, an eyed controller-arm carried by said rock-arm, means including a tension device for guiding the needle-thread from the source of 100 supply directly to the controller-arm, and actuating mechanism for the rock-arm whereby the controller-arm is operated as a pull-off member throughout the movement of the rock-arm in one direction, and 105 as a slack-forming member throughout the reverse movement of said rock-arm.

8. In an overseaming sewing machine, the combination with a frame comprising a work-support, a standard and an arm overhanging said work-support, of a driving-shaft below said work-support, a needle, a needle-actuating rock-shaft journaled within said overhanging arm, a threaded looper, a loop-spreader, a thread controller-arm, and 110 a rock-shaft connected to and adapted to operate the loop-spreader and the controller-arm simultaneously, whereby the controller-arm acts to furnish slack thread to the spreader throughout the effective action of 115 the same and thereafter acts to set the spread and concatenated loop.

9. In an overseaming sewing machine, the combination with a frame, a work-support, a needle-bar, a needle and actuating means therefor, of two coöperating loop-engaging members moving in intersecting paths, actuating means for one of said members comprising a rock-arm mounted above said 125 work-support, a needle-thread controller and 130

- a looper-thread controller operatively carried by said rock-arm, a stitch setting member operatively carried by said needle bar, and means for disengaging thread from contact with said stitch setting member comprising an inclined arm fixed to the frame.
10. In an overseaming sewing machine, the combination with work sustaining means and a reciprocating needle, of a thread-carrying member coöperating with said needle upon one side of the work, two fixed fulcra disposed at the opposite side of the work, a rock-arm mounted upon each of said fulcra and extended therefrom in the direction of 15 the other, a link connection between said rock-arms, and a second thread-carrier sustained by said link connection and actuated thereby independently of the first-named thread-carrying member and adapted to co-operate with the needle upon the opposite side of the work from said member.
11. In an overseaming sewing machine, the combination with a horizontal work-support, a driving shaft, a needle and means connected with the driving shaft for reciprocating the same, of two coöperating loop-engaging members moving in intersecting paths and mounted respectively upon opposite sides of said work-support, and means 20 adapted to operate the upper of said loop-engaging members in a plane inclined relatively to a vertical plane through the line of feed, said means including a rock-arm actuated by connections with the driving shaft 25 independent of the needle reciprocating
- means and supported in bearings disposed obliquely of the line of feed.
12. In an overseaming sewing machine, the combination with a work-support, a straight reciprocating needle, and a thread carrying 40 looper adapted to coöperate with the needle below the work-support, of a spreader mounted above the work-support and adapted to engage the looper-loop at one side of the line of seam and lift it to a position 45 embracing the needle-path, and means whereby said spreader is caused to move in a plane oblique to both the horizontal and vertical planes through the line of feed.
13. In an overseaming sewing machine, the 50 combination with a work-support, a reciprocating needle, and looper mechanism co-operating with the needle, of needle-thread controlling means including a thread-engaging member, means for moving said member 55 to give up less thread than required by the descending needle, whereby the needle is caused to draw up and set the preceding stitch, said thread giving movement continuing during the reversal of movement of 60 the needle, thereby relieving the taut needle-thread prior to the loop-presenting operation.
- In testimony whereof, I have signed my name to this specification, in the presence of 65 two subscribing witnesses.

ALFRED GRIEB.
